(57) **CLAIM**

The ornamental design for a hand wand for massaging apparatus, as shown.

DESCRIPTION

FIG. 1 is a front perspective view of a hand wand for massaging apparatus showing our new design;
 FIG. 2 is a left side elevational view thereof, of which the right side elevational view is substantially a mirror image;
 FIG. 3 is a top plan view thereof;
 FIG. 4 is a bottom plan view thereof;
 FIG. 5 is a front elevational view thereof; and,
 FIG. 6 is a rear elevational view thereof.
